UNITED STATES PATENT OFFICE.

SWAN J. LEVEEN, OF ROCK ISLAND, ILLINOIS, ASSIGNOR TO TRIO MANUFACTURING COMPANY, OF ROCK ISLAND, ILLINOIS, A CORPORATION OF ILLINOIS.

FUSE.

1,237,211.

Specification of Letters Patent. Patented Aug. 14, 1917.

Application filed January 7, 1914. Serial No. 810,811

To all whom it may concern:

Be it known that I, SWAN J. LEVEEN, a citizen of the United States, residing at Rock Island, in the county of Rock Island 5 and State of Illinois, have invented certain new and useful Improvements in Fuses, of which the following is a specification.

The present invention has reference to certain improvements in inclosed fuses, and 10 particularly to improvements in inclosed fuses of the renewable type,—that is, of that type in which the fuse element may be replaced or renewed without the necessity of rejecting or destroying the terminal portions 15 or members of the fuse, thereby making it possible to use these terminal portions or members time after time with successive fusible members. The advantages resulting from such an arrangement are 20 manifest, and, of course, include the feature of saving in cost of replacement when the fuse has blown.

At the instant of rupture of the fusible element, gases are generated at high temperature with the result that a considerable 25 gas pressure is generated within the fuse cartridge. On account of the high temperature generated at the instant of rupture it is very important to the successful and fire 30 proof operation of the fuse that the molten metals and other materials should be securely retained within the cartridge so as to avoid the possibility of setting fire to adjacent structures. Furthermore, the fuse cartridges 35 are frequently mounted on finely finished and expensive switch-boards or other structures which might be seriously damaged or defaced if the cartridge were allowed to break or come apart during the circuit opening 40 operation.

It has been found a comparatively simple matter to construct the shell of the cartridge of fire resisting fiber or the like of sufficient strength to withstand the gas pressures generated 45 at high temperature at the instant of rupture, and experience has shown that the cartridge generally breaks down, if at all, by blowing off the end portions thereof. This is because, in the past, it has been difficult or impossible to securely attach the end 50 portions to the shell in such a manner that

they are removable for renewal purposes, and also in such manner as to give the necessary strength to withstand the shocks and pressures generated at the time of rupture. 55

One of the main objects of the present invention is to so construct the fuse cartridge that the removable end portions thereof can be connected to the end portions of the shell in such a secure, and pressure and shock 60 resisting manner that they will not blow out at the instant of rupture, thereby overcoming the difficulty or objection above noted. Nevertheless, to so construct and relate the parts that the feature of renewability shall in no wise be impaired or lessened. In this connection also it is desired to produce a construction such that the completely assembled cartridge cannot be inserted into the terminal clips of the switch- 65 board, fuse block, or the like, until the end portions have been securely connected to the shell, and a construction such that as long as the cartridge remains connected into the terminal clips the end portions cannot be 70 become loosened or disengaged from the shell. In this way assurance will be had that the end portions must be securely connected to the shell before the cartridge can be connected into the terminal clips, and that as long as the cartridge remains connected into the terminal clips such connection will be 75 maintained.

Another object of the invention has to do with the provision of a cartridge construction such that the shock or pressure generated at the instant of rupture, and under abnormal conditions in the circuit will be lessened, thereby still further increasing the "factor of safety" for a given mechanical 80 strength of the cartridge. When this feature is associated or combined with the feature of increased mechanical strength obtained by improved mechanical construction a double increase in safety of operation will 85 be secured. In this connection it is desired to so construct the cartridge that an expansion space will be provided for the purpose of allowing the gases an opportunity to expand to some degree at the instant of rupture thereby correspondingly reducing the 90 gas pressure. In connection with this fea- 95 100

ture it is desired to so construct the cartridge that during and after the rupture the gases may escape from the cartridge, but to provide such a construction that this escaping will take place at a comparatively slow rate and in a safe manner so that the escaping gases will not injure the switch-board or other structure on which the fuse may be mounted.

10 In connection with the foregoing I will state that a successfully operating inclosed fuse must be so constructed that the dampening or quenching powder will at all times closely surround the fusible element so that when the instant of rupture arrives the powder may fall in around and against the fusing mass so as to quench or break up the fuse at many points and throughout its entire length. Therefore, in connection with 20 the feature of providing an expansion space in construction I have also so constructed or arranged the parts that the powder will at all times snugly or closely contact and surround the fusible element.

25 Still another object of the invention has reference to the provision of certain improvements in the indicating device whereby an indication is given as to whether or not the fuse has been blown or remains intact. 30 In this connection it is desired to produce a construction such that a definite indication will be given, regardless of the exact position in which the fuse may be mounted, whether horizontally or vertically, and 35 whether on the top, side, or bottom of a switch-board or the like.

Other objects and uses will appear from a detailed description of the invention which consists in the features of construction and 40 combinations of parts hereinafter described and claimed.

In the drawings:

Figure 1 shows a side elevation of one 45 form of fuse structure embodying features of my invention, a corner of the cartridge being cut away to show the manner of attaching the fuse wire to one of the terminals;

Fig. 2 is a longitudinal section taken on 50 the line 2—2 of Fig. 1 looking in the direction of the arrows;

Fig. 3 is a detail sectional view of the 55 end portion of the construction shown in Figs. 1 and 2 after rupture, showing how the plug may be driven out against the cap by the gas pressure;

Fig. 4 is a detail end view of a modified 60 construction of cap, which nevertheless embodies certain of the features disclosed in the arrangement of Figs. 1 and 2, and is also a construction employing blades for insertion between the terminal clips of the switch-board or other mounting;

Fig. 5 is a detail section taken on the line

5—5 of Fig. 4 looking in the direction of the 65 arrows;

Fig. 6 is a detail section taken on the line 6—6 of Fig. 4 looking in the direction of the arrows;

Fig. 7 is a side elevation of a modified construction of fuse embodying certain of the features of invention disclosed in Figs. 1 to 6 inclusive, the fuse construction shown in Fig. 7 being of the "ferrule" type;

Fig. 8 is a detail section taken on the line 75 8—8 of Fig. 7 looking in the direction of the arrows;

Fig. 9 is a detail section taken on the line 80 9—9 of Fig. 8 looking in the direction of the arrows; and

Fig. 10 is a side view of a modified form of fusible element, the same being made of a single strip including the end terminals, instead of being in the form of a built-up strip, such as those previously illustrated.

I will first describe the construction illustrated in Figs. 1, 2 and 3, and will then describe the several modifications, pointing out wherein the features of invention are to be found in each.

The body portion of the fuse comprises a shell or the like 12 which is preferably cylindrical in form and may be made of any suitable fire-resisting insulating material, such as fiber, paper or the like. The fusible element 13 extends lengthwise within this shell, and said element may be composed of a fusible body portion 14 electrically connected to terminal portions 15 and 16, as shown in Figs. 1—9 inclusive, or it may be made from a single strip of fusible material having its body portion 17 of reduced width as compared to its end portions 18 and 19, as shown in Fig. 10. I contemplate within the scope of my invention the use of either of these forms, except as I may limit myself in the claim, although as will presently appear for some purposes it would be preferable to have the end portions 15 and 16 made from a stronger material than the body portion 14.

The central portion of the shell 12 is filled with powder 20 of any desirable composition, a number of which powders are familiar to the art and are in general use. The end portions of the shell are plugged as at 21 and 22 to retain the powder properly in the shell, the end portions of the fuse member extending through these plugs. A desirable form of material for use in making the plugs is asbestos wool, inasmuch as this is a fire resisting material, of sufficiently close texture or body to hold the powder in position, but nevertheless of sufficiently porous structure to allow the gases generated at the instant of rupture to leak or seep through and to thus escape.

In the arrangement shown in Figs. 1—6

inclusive rivets or the like 23 are extended through the shell and through the body or the end portions of the fuse member, thereby locking the fuse member in position 5 within the shell, and securely retaining the end portions in position to effectively resist tension even when the body portion 14 of the fuse has been ruptured. It is preferred that each of these rivets have its end provided with a notch or the like 24, so that after the rivet has been placed in position it may be upset and thus securely held against pulling out in either direction. On account of this upsetting it will be apparent 15 that if any attempt be made to remove the rivet the shell will be torn and thus destroyed. This is an important consideration when the fuse is to be used in some localities, inasmuch as the underwriters' specifications 20 frequently provide against a refilling of the shell itself. If the shell were to be refilled this fact could be readily detected by an examination of the shell which would show the torn portions or places where the rivets 25 had been withdrawn.

On each end of the shell there is removably mounted a cap or the like 25, the flanges 26 whereof preferably extend down along the body of the shell far enough to inclose 30 the ends of the rivets so as to protect and hide the same by covering them. A pair of angles 27 and 28 are carried by each cap, their shorter arms 29 preferably lying against the inner surface of the caps, while 35 their longer arms 30 and 31 extend out through slots in the ends of the caps. These longer arms are adapted to lie flat against the opposite sides of the end portions of the fusible member to thereby grip the same between them, and to provide firm electrical 40 contact with them. Rivets or the like 32 serve to secure the angle arms to the caps, but it is preferred that the caps be provided with somewhat elongated slots or the like 45 33 so that the rivets may have a slight amount of play with respect to the caps. This will enable the angles to adjust themselves nicely, so that a firm even contact against the end portions of the fusible member 50 will be secured.

In one form of the invention, that disclosed in Figs. 1, 2, and 3, I employ the arms 30 and 31, or one or both of them, for the purpose of securing a secure unyielding connection between the caps and the end portions of the fusible member. Inasmuch as the end portions of the fusible members are securely riveted to the shell it will be apparent that if the caps in turn be secured 55 to said end portions the caps will also be securely connected to the shell so that they will be enabled to withstand the gas pressures created at the instant of rupture. In the arrangement shown in Figs. 1, 2, and 3,

a hole or perforation 34 is provided in each 65 end of the fusible member, these holes in turn alining with corresponding holes 35 in one of each pair of the arms 30 and 31. The other of each of these arms is provided with a lug or locking member 36 which may 70 be conveniently formed by upsetting the same inward from the material of the arm, as best illustrated in Fig. 2. These lugs are adapted to seat nicely within the holes 34 of the end portions of the fusible member, and 75 when thus seated will retain the caps against endwise removal. Nevertheless by reason of the somewhat loose riveted connections the arms 30 and 31 of said angles are allowed a sufficient movement to permit them to 80 spread apart when the caps are to be mounted in position on or to be removed from the shell. It will be seen, however, that as long as the arms 30 and 31 are maintained in operative or working position, such as that 85 shown in Fig. 2, as for example when they are inserted between the terminal clips of a fuse block, the caps cannot be removed and consequently are enabled to effectively resist the gas pressures. 90

As a simple means of providing the expansion space or chamber, which was previously referred to, I seat the plugs 21 and 22 a slight distance inward from the ends of the shell so that the spaces 37 are provided between the plugs and the caps. When the gas pressure occasioned by the rupture of the fuse rises to a sufficient value the plugs will be forced outward against their respective caps, so that the volume or space which 95 the gas occupies is allowed to correspondingly increase. The amount of this increase of volume will in some cases be augmented also by reason of compression of the plugs themselves after they have been jammed 100 against the caps, inasmuch as the plugs may be made of compressible material, such as asbestos wool. 105

After the gases have been generated it is desired to allow them to escape in such a 110 manner that they will not harm or injure the fuse panel or other device on which the fuse may be mounted. For this purpose the caps are preferably perforated in their end walls so that the gases can seep or work out 115 through the perforations. As a convenient mode of construction to accomplish this result the rivets 32 may be perforated as at 38. When the plugs 21 and 22 have been driven out against their caps they will serve to seal 120 the cracks which may exist around the caps to some extent, but nevertheless the gases will escape through the plugs and the holes 38.

In the modified construction shown in Figs. 4, 5, and 6, I have illustrated a somewhat different means for effecting the connection between each cap and the corresponding end of the fusible member. In this case

1 a sliding plate or the like 39 sets onto the end of the cap, being held in place by reason of the engagement of the rivets with the elongated slots 40 of the plate. The central 5 portion of this plate is provided with an opening 41, one side of which is broader than the other. As shown in Fig. 6, the end portions of the fusible member are shouldered as at 42, so that when the plate 39 is moved 10 over into the position shown in Fig. 4 the narrower portion of the opening 41 will be brought into position and thus the plate will seat beneath the shoulders 42 and will lock the cap against removal from the end of the 15 fusible member.

The construction shown in Figs. 7, 8, and 9, embodies the features of invention previously described, but this construction is of the "ferrule" type. In this case each end 20 of the fusible member is provided with a shouldered pin 43 through which the rivets 23 previously described are passed. In this case also the caps are provided with collars or the like 44 which are threaded to take 25 onto the pins 43 in the manner best shown in Figs. 8 and 9. These collars 44 preferably extend inward some distance to seat against the plugs 21 and 22 and to provide the expansion spaces 37. In this case also 30 the end portions of the caps are to be provided with the holes 45 through which the gases are allowed to escape.

It will be seen from the foregoing that in each of the herein illustrated arrangements the end portions of the fusible member are securely riveted or otherwise connected to the shell, in such a manner that they are able to effectively resist end pull. Furthermore, in each case the construction is such 40 that the rivets or other connections may be extended through the shell at a point some distance inward from the ends thereof so as to provide an extremely firm and secure connection which will not tear out under pressure. Also in each of the foregoing arrangements the end caps are retained against 45 pulling away by reason of engagement with the end portions of the fusible member.

In each of the herein described arrangements a small fuse wire 46 is shunted across that portion of the fusible member which will be ruptured under excess load, so that at the instant when the main body of the fusible member opens the entire current will 50 be concentrated on the fine fuse wire 46. In consequence such wire will be blown almost instantly. In order to give an indication as to the condition of the main fusible member, I mount a bead or the like 47 on the fuse 55 wire 46, said bead preferably resting within a pocket or socket 48 of the shell, as best shown in Figs. 1 and 8. It is preferred that after the fuse cartridge has been made up a label or the like be pasted or otherwise se-

cured over the fuse wire 46 throughout its 65 length with the exception of that portion immediately adjacent to the bead. The result of this arrangement will be that the heat generated in the fuse wire will be rapidly dissipated from the major portion of 70 its length, with the exception of that portion immediately adjacent the bead. Therefore, the tendency will be for the fuse wire to open vigorously at the point where it supports the bead, thereby generating a quantity of gas within the socket or pocket 48. This will blow the bead out from such pocket with considerable force, so that the bead will be displaced regardless of whether the fuse be mounted horizontally or vertically, 75 and regardless of whether or not the bead be on the top or bottom side of the fuse, if the same be mounted horizontally.

From the foregoing disclosures it will be 80 apparent that in each case the end caps are connected securely to the shell, so that said caps cannot be blown off or otherwise removed from the shell except by disconnecting them in the proper manner, or by destroying the shell itself. It will also be 85 seen that in each case the connections between the caps and the shell are effected through the medium of the end portions of the fusible member, which end portions in turn are securely connected to the shell. If 90 the end portions of the fusible member were not individually connected to the shell it will be evident that they could be blown out or become otherwise displaced as soon as the fusible member had been severed, and, therefore, the independent or individual connection of the two end portions to the shell is 95 important to the obtaining of a secure connection between each cap and the corresponding end of the shell.

It will also be seen from the foregoing 100 disclosures that I have provided such a construction that the caps cannot be disconnected from the shell until the terminal portions of the fuse have been removed from their respective terminal clips, and such that said terminal portions cannot be inserted into the terminal clips until a proper connection is effected between the caps and the shell. Both 110 of these features are important in a device of this kind for the purpose of insuring a proper and satisfactory operation for the various purposes intended.

I do not limit myself to the constructions 115 herein disclosed, except as I may do so in the claim, but I contemplate within the scope of my invention any equivalent constructions operating in equivalent manners to produce equivalent results.

I claim:

As a new article of manufacture an enclosed fuse comprising a cylindrical shell of fire resisting material, a fuse plate extending

beyond each end of the shell, a pin connection from each fuse plate to the shell, a fusible member joining the fuse plates together, a removable cap closing each end of the shell, 5 clips on each cap adapted to lie against the side faces of the adjacent fuse plate, and means for rigidly connecting each cap to

the adjacent fuse plate, substantially as described.

SWAN J. LEVEEN.
